UNITED STATES PATENT OFFICE.

ROBERT J. CRAVEN, OF BATTLE CREEK, MICHIGAN.

COMBINATION BROOM AND DOOR HOLDER.

Application filed July 6, 1925. Serial No. 41,813.

This invention has reference to a combined broom and door holder in which a looped spring wire carrying rubber knobs on offset ends forms friction-tipped legs when used for a door holder and friction clamping members when used for engaging the handle of a broom, brush or other article.

Among other objects the present invention contemplates a device for the purpose that is simple in construction, economical to manufacture, neat in appearance, thoroughly practical for the purpose, easy to install, and durable. These and other objects and advantages will be comprehended from the following description taken in connection with the accompanying drawings, in which Figure 1 is a perspective view of my combined broom and door holder.

Fig. 2 is a view of the holder secured to a wall and a broom suspended therefrom.

Fig. 3 is a partial view of an opened door secured by being swung upon a resilient inclined plane formed by placing the holder with the free ends of its rubber knobs and looped end upon the floor.

Fig. 4 is a side view of the holder and a sectional view of one of its rubber knobs where a corrugated offset end of the holder is fitted.

Like marks of reference refer to corresponding parts in the different views in which A represents a spring wire looped intermediate its ends, the looped portion 1 forming a narrowed slot at the closed extremity of which a nail or screw 2 is driven into a wall for securing same. The holder at its opposite ends is somewhat spread and its ends 3 offset in parallel arrangement at right angles to the major part of the side angles of the loop and fitted with elongated rubber knobs 4, between which the handle of a broom 5 or other similar article may be thrust for temporarily securing the same.

At a point near the curved or looped extremity of the holder, the same is formed with a bend or offset 6. This offset extends away from the wall against which the holder is attached and out of alignment with the looped end 1 and the heels formed by the offset ends 3, and it performs a three-fold object: first, it has a tendency to prevent the holder from swaying sidewise by forming a three-point contact against a wall when a screw or nail is passed through the looped extremity of the holder and driven to a seat,

as shown in Fig. 2; second, it forms a brace or stop for a broom or other handle when the same is suspended between the friction rubbers 4 and against said offset; third, it forms a shoe at the looped end of the holder by bringing said loop in alignment with the free ends of the rubber knobs 4 when the latter are resting endwise on a floor, a means whereby the forked ends of the holder are elevated and form a resilient incline upon which a door may be swung to effect a buffer or stop, as shown in Fig. 3.

The rubber friction knobs 4 are formed with central cavities or holes into which corrugated or roughed ends 3 of the holder are thrust, the roughening of said ends being to prevent said knobs from becoming disengaged with ordinary usage.

The objects and advantages of my improved broom and door stop will be apparent from the foregoing description.

The device when used as a broom holder is suspended from the wall from a nail or screw driven through the eyelet-like loop to firmly secure the same to a wall, and the handle to a broom is thrust between the rubber knobs 4, the resiliency of the side members of the holder A and the elasticity of the knobs permitting said handle to be readily secured, yet having sufficient stability to prevent said handle from accidentally slipping therefrom.

The device when used for a doorholder is either placed under a door when said door is opened, or placed on a floor and the door swung upon the incline formed by the forked extremities when the rubber knobs 4 are resting with their free ends upon said floor, as heretofore set forth.

From the description given, taken in connection with the accompanying drawing, the objects and advantages of my improved broom and doorholder will, it is believed, be fully comprehended.

Having, therefore, set forth my invention, what I claim as new and desire to secure by Letters Patent, is:—

A broom and door holder comprising a spring wire bent to form a loop having two substantially equal side members with outwardly extending parallel arranged offset ends, said ends being corrugated or roughened and fitted with resilient rubber knobs, substantially as set forth.

ROBERT J. CRAVEN.
